UNITED STATES PATENT OFFICE

97,173

DESIGN FOR A FLOUR SIFTER OR THE LIKE

Charles Andrews, Rockford, Ill., assignor to The
Washburn Company, Worcester, Mass., a cor-
poration of Massachusetts

Application April 1, 1935, Serial No. 56,147

Term of patent 7 years

To all whom it may concern:

Be it known that I, Charles Andrews, a citizen
of the United States, residing at Rockford, in
the county of Winnebago and State of Illinois,
have invented a new, original, and ornamental
Design for a Flour Sifter or the like, of which
the following is a specification, reference being
had to the accompanying drawing, forming part
thereof.

In the drawing:

Figure 1 is a side view of a flour sifter or the
like showing my new design, and

Fig. 2 is a top plan view of Figure 1 on a slight-
ly reduced scale.

The circular bands contrast with the rest of
the cylindrical body of the article and match
the handle, as indicated.

I claim:

The ornamental design for a flour sifter or the
like, substantially as shown and described.

CHARLES ANDREWS.
